UNITED STATES PATENT OFFICE.

CLEMENT ADER, OF PARIS, FRANCE.

ELECTRICAL RELAY.

SPECIFICATION forming part of Letters Patent No. 256,262, dated April 11, 1882.

Application filed September 24, 1881. (No model.) Patented in France May 30, 1881, in England July 7, 1881, in Belgium July 8, 1881, in Italy August 1, 1881, in Spain October 7, 1881, and in Austria-Hungary October 29, 1881.

To all whom it may concern:

Be it known that I, CLEMENT ADER, a citizen of the French Republic, residing in Paris, France, have invented certain Improvements 5 in Electrical Relays, of which the following is a specification.

The object of my invention is to provide a relay or other electro-magnet which is exquisitely sensitive to feeble currents. My relay is 10 designed most especially to meet the wants of telephone central offices, where a relay is commonly placed in the subscriber's circuit to manipulate a local circuit which operates the annunciator, denoting that the subscriber wishes 15 to speak. The batteries at the subscribers' offices usually produce a current of but slight intensity, so that on a long line it becomes quite feeble when it reaches the central office, and hence a very sensitive relay is needed to be 20 affected by it.

In the accompanying drawings, Figures 1 to 6 show the preferred form of my relay. Figs. 5 and 6 illustrate its application in a telephone central office, and Fig. 7 shows a modification.

25 I will first describe the preferred form of my relay, referring to Figs. 1 to 4.

Figure 1 is a front elevation. Fig. 2 is a plan. Fig. 3 is a transverse section, showing part of the relay in side elevation; and Fig. 4 is a fragment of Fig. 3, showing a different method of making the connection.

A is a permanent magnet, (or it may be a continuously-excited electro-magnet,) bent so that its poles N S come near together. It is best to 35 use two of these magnets for each relay, they being arranged side by side, as shown in Figs. 1 and 2, and being oppositely polarized during their manufacture, so that the front pole of one will be a north pole, while that pole of the 40 other will be a south pole. Between the two magnets an electric coil or helix, H, is suspended from a pivot, x, above, so that it hangs near the poles of the magnets and between the poles of the two magnets, being free to swing in a 45 plane parallel with the magnets. In order to bring the magnetic attraction as near the coil H as possible, angle-pieces G G, of soft iron, are fixed to the poles of the magnets and project toward the coil H. The pivot x is mounted 50 in two supports, a a, and the stem h of the coil H is continued above the pivot and bears

a counter-weight, P, which may be screwed up or down, in order that it may more or less neutralize the weight of the coil H. In Fig. 2 the counterpoise P is omitted.

55 On the stem h is fixed the contact-pin T, which, when the coil H swings toward the front or back, strikes one of two opposite contact-arms, E E, and closes the local circuit. The arms E are fixed to the block a and connect through it to the metal of the magnets, whence connection is established with one pole of the local battery, as will be presently described. The contact T is at other times insulated from the arm E, either by the block b, 60 in which the pivot-pins x are embedded, being of insulating substance or otherwise. The terminal wires of the coil H are lettered F F', 65 and they connect, through binding-plates f f', and binding-posts or otherwise, with the line-wires leading to the subscriber's office. In Fig. 3 I have shown these wires F F' as connected through screws entering the block b; but in Fig. 4 I have shown them as simply passed over the insulated pivot-pins x x.

70 It will now be evident to those versed in physics that if a current be sent through the line-circuit from the subscriber's office it will traverse the coil H and render it magnetic, so that a mutual attraction will be established between 75 it and the rear poles, S N, of the pieces G G and a repulsion between it and the front poles, N S, or vice versa, depending on the direction of the current. In either case the point T touches one of the arms E and closes the local 80 circuit. The residual magnetism of ordinary relays and other electro-magnets I overcome by omitting from my coil H the usual magnetic core of soft iron, either using no core or else a core of some non-magnetic metal. This is an 85 important and valuable feature in my relay, adding greatly to its sensitiveness, which by the use of the counterpoise P and the omission of all retracting-springs and other obstacles to the manifestation of magnetic action is already extreme.

90 Fig. 6 shows in partial diagram the accessories at the central office in connection with a subscriber's circuit.

95 C is the subscriber's circuit, a part only of which is shown.

R is the relay hereinbefore described, the

magnets **A A** being omitted and the remaining parts designated by the same reference-letters used in Figs. 1 to 4.

5 **L** is a local circuit, arranged to be closed by the relay at **T E**. **l** is a battery in said circuit.

K is the indicator already referred to, which consists of an electro-magnet, **k**, included in the circuit **L**, an armature **detent-lever m**, and a hinged drop or screen, **n**, which when released by the charging of the magnet drops and exposes the number corresponding to the subscriber's circuit **C**, all as is common; and **D** is a commutator, on the principle of the "American jack-knife" commutator, for connecting by means of conducting pegs and cords the subscribers who wish to converse.

10 The preferred arrangement of my relays for telephone central offices will be best understood from Fig. 5, where the relays are viewed as in Fig. 1, and where the circuit-connections for eight subscribers are shown in diagram. These circuits **C C** are numbered 1, 2, 3, &c., and the relays **R R**, indicators **K K**, and commutators **D D** are correspondingly numbered.

15 It will here be observed that one local battery **l** serves for all the circuits **L L**, and that the relays **R R** are arranged in battery, the magnet **A** on one side of one coil **H** serving as that on the other side of the next coil. The magnets **A A** are all metallically connected with a screw, **q**, whence a wire leads to one pole of the battery **l**.

20 It is evident that the form of my relay shown in Figs. 1 to 4 is not necessarily the only form of which it is capable, since the same essential construction may be carried out by constructions apparently very different—as, for example, by that shown in Fig. 7, where the axis of the pendulum is vertical, so that the coil moves in a horizontal plane close along a horizontally-arranged bar-magnet, moving toward one pole or the other of the magnet, according to the direction of the current traversing it.

25 I am aware that various arrangements of a movable coil in connection with fixed magnets have been suggested, a common method being to inclose one pole of the magnet in the coil. My arrangement differs from all others with which I am acquainted, in that the coil incloses no magnet nor core, and hence the retarding effect of residual magnetism is entirely overcome. Furthermore, I cause the coil to move in a direction at right angles to its axis, and in my preferred construction I balance the magnetic action by disposing opposite poles on opposite sides of the coil and equidistant therefrom.

30 I claim as my invention—

60 1. The combination of an electric coil having no core, delicately mounted and free to move

in a direction at right angles, or substantially so, to its axis, with a magnetic pole arranged within attractive range of said coil and to one side of its path of motion, substantially as set forth.

2. The combination of an electric coil having no core, delicately mounted and free to move in a direction at substantially right angles to its axis, with two unlike magnetic poles arranged opposite to each other within attractive range of the coil and one on each side of its path of motion, whereby the coil when attracted to them will move between them, substantially as set forth.

3. The combination of a delicately-mounted electric coil, having no core and free to move in a direction substantially at right angles to its axis, with two unlike magnetic poles arranged within attractive range of the coil, both on the same side of its path of motion, and the two on opposite sides of its normal or intermediate position, substantially as set forth.

4. The combination of a delicately-mounted electric coil, having no core and free to move in a direction at substantially right angles to its axis, with four magnetic poles arranged in two pairs, with like poles diagonally opposite to each other and unlike poles directly opposite to each other, the two unlike poles of each pair arranged on opposite sides of the path of movement of the coil, and the two pairs arranged one on each side of the normal or intermediate position of the coil, and within attractive range thereof, substantially as set forth.

5. The combination, to form a relay, of a pendulously-hung stem or lever, an electric coil mounted upon one arm thereof, an adjustable counterpoise mounted on the opposite arm thereof, a contact-point borne by said stem or lever, a fixed contact-stop against which said point may impinge upon the movement of the coil from its normal position of rest, and one or more fixed magnetic poles arranged within attractive range of the coil, substantially as set forth.

6. The combination of a series of magnets, **A A**, arranged side by side, their pole-extensions **G G**, the blocks **a a**, mounted on the magnets, the pendulous stems **h h**, arranged one in each of the spaces between the magnets and hung from the blocks **a a**, the contact-pins **T T**, the contact-stops **E E**, and the coils **H H**, substantially as set forth.

In witness whereof I have hereunto signed my name in the presence of two subscribing witnesses.

CLEMENT ADER.
